ESCUOTCHEON FOR COMBINED EIGHT TRACK TAPE PLAYER AND TUNER

Richard H. Seager, Manlius, N.Y., assignor to
General Electric Company

Filed Apr. 7, 1972, Ser. No. 242,295

Term of patent 14 years

Int. Cl. D14—03

U.S. Cl. D26—14 B

FIG.4

FIG.5

FIG. 1 is a front elevation view of a combined eight track tape player and tuner in accordance with my design; FIG. 2 is a top plan view; FIG. 3 is a bottom plan view; FIG. 4 is a left side elevation view; and FIG. 5 is a right side elevation view.

The broken lines are shown for illustrative purposes only.

I claim:

The ornamental design for an escutcheon for combined eight track tape player and tuner, as shown and described.
